CONVERTIBLE SUITCASE

Donald C. Powell, Los Angeles, Calif., assignor of one-tenth to Gadget-Of-The-Month Club, Inc., Los Angeles, Calif., a corporation of California

Application October 8, 1956, Serial No. 614,558

1 Claim. (Cl. 190—44)

This invention relates to new and useful improvements in suitcases or other similar pieces of luggage, and the principal object of the invention is to substantially enhance the utility and functional adaptability of articles of this type.

The above object is attained by the provision of what may be called a convertible suitcase, composed primarily of a main body section and a pair of side sections, together with means for selectively attaching the side sections to the main body section and to each other. Thus, when the side sections are attached to the main body section they coact therewith to form a relatively large suitcase. However, when they are detached from the main body section and attached together, they form a relatively small and thin case, such as an overnight case, quite independently of the main body section.

An important feature of the invention therefore resides in the arrangement of the suitcase whereby it may be converted from a large case to one of a smaller capacity, as desired.

Another feature of the invention resides in the arrangement of separable hinge members and fastener members on the various sections of the suitcase, said hinge members and fastener members being selectively usable whereby the case sections may be variously grouped together, as aforesaid.

Another feature of the invention resides in the provision of a carrying handle together with means for attaching the same either to the main body section or to one of the side sections of the suitcase, whereby the same handle may be used with the case in either one of its two different forms.

Some of the advantages of the invention reside in its simplicity of construction, in its adaptability to economical manufacture and in the saving and convenience which it affords by eliminating the need for purchase of two different cases such as are provided by a single case constructed in accordance with the invention.

With the foregoing more important objects and features in view and such other objects and features as may become apparent as this specification proceeds, the invention will be understood from the following description taken in conjunction with the accompanying drawing, wherein like characters of reference are employed to designate like parts and wherein:

Figure 1 is a perspective view of the suitcase with the side sections thereof attached to the main body section;

Figure 2 is a vertical sectional view, taken substantially in the plane of the line 2—2 in Figure 1;

Figure 3 is a perspective view of a case formed only by the two side sections;

Figure 4 is a fragmentary underside perspective view showing a typical arrangement of two coacting hinge members;

Figure 5 is a fragmentary group end view of the three sections of the case and the coacting fastener members thereon; and

2

Figure 6 is a fragmentary elevational view of the detachable handle.

Referring now to the accompanying drawing in detail, the suitcase constructed in accordance with the invention is designated generally by the reference numeral 10 and embodies in its construction a centrally disposed main body section 11 and a pair of complementary side sections 12, 13. The side sections 12, 13 are disposed at opposite sides of the main body section 11 so as to constitute covers therefor, and if desired, the side edges of the main body section may be upwardly convergent so that the suitcase is upwardly tapered, as shown. It will be also noted that the side sections are substantially thinner than the main body section.

15 Sets of separable, selectively usable hinge members are employed for attaching the three sections of the suitcase together. These hinge members may be of any suitable conventional type and, for illustrative purposes in Figure 4 there has been shown a female hinge member A 20 coacting with a male hinge member B. The female hinge member comprises a tubular body 14 provided with a lateral plate 15 whereby it may be secured to a section of the case by suitable rivets, or the like, 16. The male hinge member comprises a pin 17 projecting longitudinally from a cylindrical body 18 of a larger diameter than the pin, so as to form a shoulder 19 to abut the body 14 of the female hinge member when the pin 17 is slid into the body 14. The body 18 of the male hinge member is also provided with a laterally projecting mounting plate 25 20 for attachment thereof to a section of the suitcase.

The hinge members are used in pairs at each of the adjacent lower edges of the several case sections, the female hinge members A being secured to the side section 13 and to the edge of the main section 11 adjacent the side section 12, while the male hinge members B are secured to the side section 12 and to the edge of the main section 11 adjacent the side section 13, as indicated in Figure 2.

40 The male and female hinge members may be connected together by relative longitudinal shifting of the adjacent case sections as shown by the arrows 21, 22 in Figure 4, whereby the pin 17 of the male hinge member may be slid into the body 14 of the female hinge member. Separation of the hinge members is effected by relative sliding of the case sections in the opposite directions.

45 It will be apparent from the foregoing that the three sections of the suitcase may be attached together as shown in Figures 1 and 2 by engaging the female hinge members A on the side section 13 with the male hinge members B on the adjacent edge of the main section 11, and similarly engaging the female hinge members A on the main section 11 with the male hinge members B on the side section 12.

50 However, by separating the several hinge members, the main case section 11 may be completely removed, whereupon the female hinge members A on the side section 13 55 may be engaged with the male hinge members B on the side section 12, whereby the two side sections 12, 13 may be used to form a case as shown in Figure 3, independently of the main body section 11. The case so formed is, of course, substantially smaller and flatter than the original case shown in Figure 1 and, as such, 60 may be effectively used for overnight purposes, or the like, where a relatively large case is unnecessary.

65 When the suitcase is assembled as shown in Figure 1, the side sections 12, 13 may be opened on their hinges to facilitate access to the interior of the case from either side. On the other hand, when the case is assembled as shown in Figure 3, the two sections 12, 13 may be opened on their hinges into a flat, co-planar relationship, whereby access to both side sections of the case may be 70 easily had.

In order to hold the case in a closed position, sets of

fastener members C and D are provided on the various case sections. These fastener members may be of any suitable conventional form, and for illustrative purposes have been shown in Figure 5 as comprising swingable clasps 23 carried by bases 24 in the fastener members C. In the members D there are provided hook-shaped detents 25 mounted on bases 26 and adapted for locking engagement with the clasps 23 of the members C.

The arrangement of the fastener members C, D is similar to the arrangement of the hinge members A, B, on the various sections of the suitcase. Thus, the fastener members C are provided at the top edge of the side section 12 and at the top edge of the main section 11 adjacent to the side section 13. The fastener members D are provided at the top edge of the side section 13 and at the top edge of the main section 11 adjacent the side section 12.

Accordingly, when the case is assembled as shown in Figure 1, the various sections may be fastened against opening by engaging the members C on the side section 12 with the members D on the main section 11, and similarly engaging the members C on the main section with the members D on the side section 13. On the other hand, when the main section 11 is removed and the side sections are assembled to form the case as in Figure 3, the fastener members C on the section 12 are engaged with the fastener members D on the section 13.

It may be again noted that the particular form of the hinge members A, B and of the fastener members C, D has been shown for illustrative purposes only, and that any conventional separable and selectively usable hinge and fastener members may be utilized.

The suitcase is provided with a carrying handle 27 which may be attached either to the main section 11 or to one of the side sections, such as for example, the side section 12. This may be facilitated by forming the handle from resilient material so that the end portions thereof may be drawn toward each other as shown by the dotted lines 27a in Figure 6. The end portions of the handle, when sprung back to their normal position, are received in a pair of sockets 28 secured to the top of the main section 11, or in a pair of similar sockets 28a secured to the top of the side section 12. Thus, the entire assembly as shown in Figure 1 may be carried by the handle 27 or, if the main case section 11 is removed, the case as shown in Figure 3 may be carried by the same handle after removing the latter from the case section 11 and applying it to the sockets 28a on the case section 12. As already stated, the handle may be removed from the sockets 28 or 28a by simply pressing the end portions of the handle toward each other as indicated at 27a whereby to withdraw them from the sockets. However, it is to be understood that this detachable mounting of the handle is also shown for illustrative purposes only, and that any other conventional handle attaching and detaching means may be employed.

The side sections 12, 13 are preferably provided at the bottom thereof with button-shaped feet 32 which

support the case in an elevated position above a ground surface or floor, regardless of whether the case is assembled as in Figure 1 or in Figure 3. Thus, in either instance, the provision of additional feet on the bottom of the main case section 11 is unnecessary.

The case sections 11, 12 and 13 may be formed from any suitable material in accordance with conventional practice well known in the art of luggage making. Moreover, the case may be of any desired size and shape, not necessarily of a rectangular configuration shown in the drawings.

It will be observed from the foregoing that the invention provides a convertible suitcase, capable of use in either of two different forms and correspondingly different capacities, thus affording a saving and convenience not known in cases of conventional types.

While in the foregoing there has been disclosed the preferred embodiment of the invention, various modifications may become apparent to those skilled in the art to which the invention relates. Accordingly, it is not desired to limit the invention to this disclosure, and various modifications may be resorted to, such as may lie within the spirit and scope of the appended claim.

What is claimed as new is:

A convertible suitcase comprising a main body section, first and second side sections disposed at opposite sides of said main body section and constituting covers therefore, a first set of hinge members and a first set of fastener members provided at the respective lower and upper edges of the first side section and at the respective lower and upper edges of said main body section adjacent the second side section, a second set of hinge members and a second set of fastener members provided at the respective lower and upper edges of the second side section and at the respective lower and upper edges of the main body section adjacent the first side section, the first and second sets of hinge members and the first and second sets of fastener members being separably connectable, whereby the side sections may be selectively hinged and fastened to said main body section and hinged and fastened to each other to form a case independently of the main body section, a carrying handle, means for selectively attaching said handle to said main body section and to one of said side sections, and feet provided on lower edges of said side sections and supporting said main body section in an elevated position when the main body section and the side sections are hinged and fastened together by said fastener members.
